CLAIM

The ornamental design for a controller for pneumatic compression device, as shown and described.

DESCRIPTION

FIG. 1 is a perspective view of a controller for pneumatic compression device, showing our new design;

FIG. 2 is a front elevational view thereof;

FIG. 3 is a rear elevational view thereof;

FIG. 4 is a right elevational view, the left elevational view being a mirror image thereof;

FIG. 5 is a top plan view thereof; and,

FIG. 6 is a bottom plan view thereof.

(Continued)

The broken lines in the figures show portions of the controller for pneumatic compression device that form no part of the claimed design.
